P. T. Remond
ATTORNEY

UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF NEW JERSEY.

VEHICLE BODY.

Application filed January 17, 1925. Serial No. 3,057.

This refers to vehicle body constructions and particularly to body partitions positioned between the front and rear seats of a closed vehicle body such as are provided in

5 that type of closed bodies commonly known as "berlines" or in other types of closed bodies having a plurality of rows of seats wherein it is desired to separate one row of seats from the other.

10 One of the objects is to provide a detachable body partition applicable to a sedan body for converting the same into that type of body commonly known as the "berline" and which may be removed when it is desired to convert the body back to a sedan

15 type.

A further object is to provide a body partition for bodies of the sedan type which when in position will have the appearance 20 of having been permanently built into the body.

A further object is to provide a body partition with a trim stick for concealing the corner irons which secure the partition to 25 the vehicle body.

A still further object is to provide a body with a trim stick covered with the same piece of material as the partition proper which provides a hinge for the same, in 30 order that after the partition has been assembled, the trim stick may be swung around and secured to conceal the attaching corner irons.

These being among the objects of the 35 present invention the same consists of certain features of construction and combination of parts to be hereinafter described with reference to the accompanying drawing, and then claimed, having the above and 40 other objects in view.

In the accompanying drawing which illustrates a suitable embodiment of the present invention and in which like numerals refer to like parts throughout the several 45 views,

Figure 1 is a side view of an automobile of the closed type showing in dotted lines the location of the body partition over the back of the front seat.

50 Figure 2 is a fragmentary perspective view showing the body partition in operative position, with the trim stick bent back to allow access to the securing means or corner iron.

55 Figure 3 is a fragmentary perspective

view showing the body partition in complete assembled position, that is, with the trim stick secured in place over the corner irons.

Figure 4 is a perspective view of the complete unit before it is installed in the vehicle body. 60

Figure 5 is a fragmentary, horizontal sectional view showing the method of attaching the body partition to the rear front 65 door pillar and showing the trim stick in unsecured or bent back position.

Figure 6 is a fragmentary sectional view identical to Figure 5, but showing the trim 70 stick in secured position.

In the past, body partitions have not been adapted to convert an ordinary sedan body into a "berline" type and have been built into the body as a permanent structure at the time the body was constructed. 75 The body partition 10 is built up as a single unitary structure and then installed in the body 11 over the back of the front seat 12 as shown in Figure 1 by the dashed lines.

The partition 10 consists of upper and 80 lower rails 13 and 14 respectively, conforming in shape to the upper portion of the back of the front seat 12, connected together by end members 15 and intermediate members 16. Between the intermediate members 16 slideable glass windows such as 17 are preferably provided, and curved glass windows 18 are preferably provided between each intermediate member 16 and the adjacent end member 15. 85

The partition 10, with the exception of the windows, is covered with suitable upholstery material 19, preferably of the same kind, finish and color as that used for the interior of the rest of the vehicle body 90 which is to receive the partition. The lower rail 14 is adapted to seat on the upper edge of the back of the front seat, as shown in Figure 3, and the upper rail 13 is adapted to contact against the top inner 95 lining 20 of the vehicle body. The end members 15, when the partition 10 is in operative position in the vehicle, seat snugly against the inside face of the door pillars 21, and are secured thereto by a plurality of 100 angular brackets 22, one leg of each of which is set into the end member 15 so as to be flush therewith, and the other leg of which contacts with and is secured to the door pillars 21 preferably by screws or the 105

110

like. A trim stick 23 covered by an extension of the upholstery material 19, is hingedly connected to the end members 15 and is shaped to form a continuation of the 5 end members 15 and to blend the edge to the partition 10 into the side of the door pillars 21 when in operative position. The trim sticks 23 are provided with pockets 24 on their inner faces for receiving the legs 10 of the brackets 22 when the trim sticks are in finally assembled or operative position, so that they may abut against the adjacent edge of the door pillars 21.

In applying the partition to the vehicle 15 body, which may be of any enclosed type having spaced front and rear seats, and which is herein and in the claims designated as a sedan type of vehicle body, the partition 10 is placed with the lower rail 14 on the 20 upper rear edge of the front seat 12, the upper rail 13 contacting against the top inner lining 20 and the end members 15 resting against the door pillars 21. The trim stick 23 is then bent back as shown in Figures 2 and 5 to expose the angular bracket 25 members 22, one leg of each of which is secured to the end members 15, and screws are passed through the other leg into the door pillars 21, thus securing the partition 10 securely in place. After the partition 10 is thus secured in place the trim sticks 23 are allowed to resume their normal or operative 30 position as shown in Figures 3, 4 and 6, and a few small nails or brads are driven 35 through them into the door pillar to hold the trim stick in place, the heads of the brads or nails being concealed by the nap of the upholstery if such a type of upholstery is used. It will be evident that the means for 40 securing the partition in place is thereby effectually concealed, and gives the partition an appearance of having been built in position instead of the readily attachable and detachable device that it in reality is. It will 45 be understood, that if desirable the top and bottom rails 13 and 14 and also the vertical posts can be made adjustable so that the partition can be adjusted to fit various sizes of 50 bodies and also that formal changes may be made in the specific embodiment of the invention described without departing from the spirit and scope of the broad invention, the scope of which is commensurate with the 55 appended claims.

What I claim is:—

1. In combination with a vehicle body, an attachable partition having transparent closures and end rails supporting said closures, and means including a trim stick for concealing 60 said end rails when in operative position.

2. In an attachable body partition for closed vehicle bodies of the sedan type, corner

members for securing the ends of said partition to the sides of said body, and means 65 including a trim stick for concealing said corner members.

3. In combination with a body partition for converting closed bodies of the sedan type to that type having a separated driver's 70 compartment, corner members for securing the ends of said partition to said body, trim sticks for concealing said corner members, and upholstery material covering both said trim sticks and portions of said partition, 75 said upholstery material providing hinged supports for said trim sticks.

4. In an attachable body partition for closed vehicle bodies of the sedan type, angle members for securing the ends of said partition to the sides of said body, and trim sticks hingedly attached at the ends of said partition for concealing said angle members. 80

5. In a removable body partition for closed vehicles having front and rear seats, 85 said partition providing an enclosure for said front seat, angle members for attaching the ends of said partition to the sides of said body, trim sticks for concealing said angle members and upholstery material for 90 both said trim sticks and said partition, said upholstery material providing hinged supports for said trim sticks on said partition.

6. Means for partitioning the driver's seat from the rear seats of a sedan type vehicle, 95 comprising a frame having transparent closures extending between the upper edge of the driver's seat and the top of the vehicle between the opposite sides thereof, said frame being provided with vertically extending 100 end members and covered with upholstery material, means for securing said end members to the side of said vehicle, and means comprising a trim stick hingedly secured to said end members by a continuation 105 of said upholstery material for concealing said securing means.

7. In combination with a vehicle body provided with front and rear seats having backs, a partition comprising a frame and 110 enclosures supported thereby, the bottom frame member seating on and conforming in shape to the front seat back, the vertical frame members detachably secured to said body, and means to conceal the attaching 115 means for said vertical members.

8. In combination with a vehicle body, an attachable partition having transparent closures and end rails supporting said closures, means for securing said end rails to 120 said body, and a hinged member for concealing said securing means.

Signed by me at Detroit, Michigan, U. S. A., this 12th day of January 1925.

JOSEPH H. BOURGON.
